UNITED STATES PATENT OFFICE.

MARCUS A. ERICKSON, OF MINNEAPOLIS, MINNESOTA.

DOUBLE-ACTING SPRING-HINGE.

No. 901,796.

Specification of Letters Patent.

Patented Oct. 20, 1908.

Application filed December 19, 1907. Serial No. 407,108.

To all whom it may concern:

Be it known that I, MARCUS A. ERICKSON, of Minneapolis, Hennepin county, Minnesota, have invented certain new and useful 5 Improvements in Double-Acting Spring-Hinges, of which the following is a specification.

My invention relates to hinges designed for use on double acting doors or those 10 adapted to swing both ways.

The object of my invention is to provide means for holding the door in an open position when swung in either direction.

A further object is to provide means 15 whereby any further movement of the door after passing the normal stopping point will be cushioned by the spring, thus rendering door stops unnecessary.

A still further object is to provide a double acting hinge which while holding the door in an open position, will when the door is pushed beyond such position and released, allow it to close, thus permitting the person passing through the door to cause it 25 to stay open or closed as desired.

My invention consists generally in various constructions and combinations, all as hereinafter described and particularly pointed out in the claims.

30 In the accompanying drawings, forming part of this specification, Figure 1 is a detail view partially in section illustrating the application of my invention to a double swing door. Fig. 2 is an edge view of the same. Fig. 3 is a sectional view on the line $x-x$ of Fig. 2 looking in the direction of the arrow. Fig. 4 is a similar view on the line x^a-x^a of Fig. 1, also looking in the direction of the arrow. Fig. 5 is a sectional 35 view on the line A—A of Fig. 1. Fig. 6 is a sectional view on the line $y-y$ of Fig. 1. Fig. 7 is a sectional view on the line $z-z$ of Fig. 1. Fig. 8 is a detail sectional view showing the door in its open position. Fig. 40 9 illustrates the position of the parts when the door is swung past its normal open position, and the axis of the door hinge plate is transferred from one pivot to another. Fig. 45 10 is a detail view illustrating a modified construction. Fig. 11 is a sectional view on the line y^a-y^a of Fig. 10. Fig. 12 is a sectional view on the line x^a-x^a of Fig. 10. Fig. 13 is a sectional view on the line z^a-z^a of Fig. 10. Fig. 14 is a view corresponding 50 55 to the mechanism shown in Fig. 10 illus-

trating the open position of the door. Fig. 15 corresponds to Fig. 9 and illustrates the change of the pivot of the door hinge plate from one center to another when it is swung past the normal stopping point.

In the drawing, 2 represents a door casing and 3 a double acting swing door of ordinary construction. The top of this door has a pivotal connection 4 with the casing of the ordinary type. At the bottom a base 60 plate 5 is provided, having a ball bearing 6 for a door plate 7 that is secured to the bottom and rear edge of the door by any suitable means. A dust ring 6' is provided to inclose the said ball bearing and is located 65 between the box and the base plate. The lower edge of the door is mortised to receive the box 8 in which the mechanism of the double acting spring hinge is arranged. This box may be made in various ways and 70 I do not wish to confine myself to the particular construction illustrated herein. A disk 9 has a plain round shank 10 arranged to project through an opening in the plate 7 and is provided with a shoulder 10' to engage the base plate 5. Below this shoulder 75 the shank is diamond-shaped in cross section, though it may be square or polygonal, if preferred, and enters into a correspondingly shaped opening in the plate 5, and is 80 provided with a nut 11 by means of which the disk 9 and the base plate may be securely clamped together.

Upon the disk 9, pins 12 and 12^a are mounted, said pins being substantially 85 square in cross section and fitting within an opening 13 in a plate 14 which has irregular cam shaped edges around the said opening. A projection 15 formed on said plate extends between the pins in their normal 90 position when the door is closed, and recesses 16 and 17 are formed in the plate at one side of the opening with a projection 18 95 between them, and similar recesses 16^a and 17^a with a projection 18^a are provided on the opposite side of the opening. The plate 14 is provided with a shank 19 fitting within one end of a coiled spring 20 whose opposite end is secured to a stud 21. A plate 22 is secured to the plate 7 and box 8, and has a 100 hole 22' in which the stud 21 slides. The stud 21 has an adjusting nut 23 by means of which the tension of the spring may be regulated and its pressure on the cam plate and the pins controlled.

In Fig. 8 the device is illustrated with the parts in the position assumed when the door is open or swung to a point a little beyond a right angle to the normal or closed position of the door. In this position the tension of the spring will be applied to draw the cam plate against the pins and hold the door in an open position or at a point slightly beyond the center. A slight pressure will be sufficient to overcome the tension of the spring and allow the door to close, but until such pressure is applied the door will remain open without the use of a wedge or any other securing means.

In Fig. 9 the hinge is illustrated in the position assumed when the door is pushed still further open, in which case the cam plate will cease to swing on the pin 12^a as a center and its axis will be transferred to the pin 12 and the leverage on the spring will be increased and it will act as a cushion to resist the further opening movement of the door, and dispense with the use of a stop generally employed to prevent a door from striking the wall or casing, the cushion action of this spring offering a gradually increasing resistance to the movement of the door and preventing any damage or strain to the door or the hinge in case it is pushed beyond the normal stopping point.

In Fig. 12 a modified form of cam plate 24 is shown, the pins mounted on the disk having anti-friction rollers 25 thereon, and the edge of the cam plate around the opening being modified to suit the changed form of the pins. The principle and mode of operation, however, is the same as that of the device described.

A yoke 27 has outwardly turned lugs 27^a formed thereon projecting into holes in the top and bottom of the box and forming pivots on which the yoke has a limited horizontal movement with the cam plate. The end of the yoke has a hole to receive the shank 26 of the cam plate and the plate 28 is slideable on said shank and has guides 29 which hold the plate and the spring in position within the yoke. The pivots 27 allow the yoke and spring to oscillate and follow the movement of the cam plate, as indicated in Fig. 14. This construction differs from that heretofore described in that the plate through which the threaded stud of the former construction passes, is rigid, and the spring itself is flexed to follow the movement of the cam plate. The lock nut on the threaded end of the stud 26 corresponds to the one described, and the tension of the spring may be regulated by the adjustment of this nut.

The operation of the mechanism illustrated in Fig. 12 is the same as that of the construction first described. The door when opened will be swung back to a position substantially at right angles to its closed position

and when the cam plate has been moved slightly past the center, the pins or studs will enter the recesses in the plate and the door will be held in that position without the use of any fastening means and will yield against the tension of the spring if the door is pushed still farther open.

If it is desired to close the door the operator may push it open a little further, and upon releasing it the door will swing entirely shut.

In devices of this kind as usually made the hinges would not stop in an open position without the use of wedges or some form of stop. Those that do remain open when the hinge has been swung past the center of the door pivot, will not close themselves after being swung past the normal stopping point. Hence I regard this feature of my invention as a valuable improvement over devices of this kind as usually made.

The various details of construction may be modified without departing from the spirit of my invention.

I claim as my invention:

1. A double acting spring hinge having means for holding the door in an open position, said holding means permitting the door to close through its momentum when pushed farther open, or beyond the point where said holding means is operative, and released.

2. A double acting swing door in combination, with a spring hinge therefor, said hinge including means for holding said door to prevent it from closing when swung open past a predetermined point, and a spring device permitting the further opening of the door, but yieldingly resisting such movement, for the purpose specified.

3. A double acting swing door in combination with a double acting spring hinge, said hinge comprising stationary pins and a plate having cam edges arranged to engage said pins and travel thereon, and said plate having recesses in its opposite sides to receive said pins when the door is swung to an open position, the walls of said recesses engaging said pins and holding the door in its open position, and a spring attached to said plate and arranged to be put under tension by the movement of the door, substantially as described.

4. The combination, with a double swing door, of a double acting spring therefor and comprising a disk and pins mounted thereon, a plate having cam edges arranged to bear on said pins and a spring connected with said plate, said plate traveling on said pins as the door is swung to an open position and having recesses to receive said pins when the door is open, a spring device arranged to hold said plate in engagement with said pins and thereby lock the door at a predetermined point in its open position, said

plate swinging on one of said pins as a pivot from the closed position of the door to its open position, and the axis of said plate being transferred from one pin to the other, and the resistance of said spring increasing thereon when the door is pushed beyond its normal open position.

In witness whereof, I have hereunto set my hand this 13th day of December 1907.

MARCUS A. ERICKSON.
